Specification for Design.

Patented Feb. 22, 1921.

Application filed August 7, 1920. Serial No. 402,023. Term of patent 14 years.

To all whom it may concern:

Be it known that I, REUBEN B. BENJAMIN, a citizen of the United States, residing at Chicago, in the county of Cook and State of Illinois, have invented a certain new, original, and ornamental Design for a Current-Tap, of which the following is a specification, reference being had to the accompanying drawing, forming a part thereof.

Figure 1 shows a side elevation of a current tap embodying my invention; and Fig. 2 shows a side elevation of the current tap seen from the right of Fig. 1.

I claim:

The ornamental design for a current tap substantially as shown.

REUBEN B. BENJAMIN.
